Specification for Design.

Patented May 13, 1919.

Application filed October 30, 1918. Serial No. 260,370. Term of patent 3½ years.

To all whom it may concern:

Be it known that I, GEORGE H. CLARKE, a citizen of the United States, residing at River Point, West Warwick, in the county of Kent and State of Rhode Island, have invented a new, original, and ornamental Design for Cotton Lace, of which the following is a specification, reference being had to the accompanying drawing, forming part thereof.

The figure shows a front face view in elevation of a portion or strip of cotton lace showing my new design.

I claim:

The ornamental design for cotton lace, as shown.

GEORGE H. CLARKE.
